YARN HANDLING AND SEVERING MECHANISM FOR CIRCULAR KNITTING MACHINES AND METHOD

Vaughn H. Butler, Harriman, Tenn., assignor to Burlington Industries, Inc., Greensboro, N.C., a corporation of Delaware

Application March 14, 1958, Serial No. 721,452

7 Claims. (Cl. 66—140)

This invention relates to circular knitting machines, and in particular to improved means and methods for handling and severing yarns on the dial caps of multiple feed knitting machines.

In the knitting of tubular articles such as seamless hosiery, frequent yarn changes are commonly effected in the course of the knitting cycle. In the case of hosiery, for example, the welt and leg may be knitted of different yarns, and heavier yarns are frequently employed in the heel and toe. At each yarn change, an inactive yarn is dropped into the needles for knitting and an active yarn is withdrawn from the knitting a few needles later. At least two yarn ends extend from the resulting yarn lap, and these are commonly severed so as to be an inch or two in length. Since yarn ends of such length are easily noticeable and unsightly, they must be removed, and this is usually done individually and manually during inspection. The yarn ends are clipped down to $\frac{1}{4}$ " or $\frac{3}{8}$ ", which is commercially satisfactory. The clipping operation is obviously time-consuming and expensive, and exposes the stockings to possibility of damage. In multiple feed knitting, more than two yarn ends extend from each yarn lap, whereby the clipping problem is magnified.

A principal object of the present invention is the provision of novel means and methods for positioning yarns over the dial caps of multiple feed machines for clipping, and automatically severing the yarns close to the fabric during yarn changes, with such reliability and control as to eliminate subsequent inspection and clipping of free ends. In accordance with the invention, a single yarn handling device and a single shear are provided and utilized to handle and clip yarns from at least two distinct feed stations. The invention also contemplates the close clipping of the ends of newly inserted and withdrawn yarns from a plurality of feed stations, preferably with a single shear stroke.

Another object of the invention is the provision of improved suction means for tensioning and controlling yarns on the dial cap of the machine, and means for positive and precise control of the air flow. Particularly, means are provided to terminate air flow in precisely timed relation with operation of the shear, and subsequent to the shearing operation. Delayed air flow termination is accomplished by means distinct from the shear operating means. A related object is the provision of means for delayed shear operation, that is, for operation of the shear after movement of the main pattern drum has terminated and while the latter is at rest, and alternative means for operating the shear in time with movement of the main pattern drum. Further objects will be in part evident and in part pointed out hereinafter.

The invention and the novel features thereof may best be made clear from the following description and the accompanying drawings, in which:

Figure 1 is a top plan view of a preferred embodiment of the invention in operative association with related parts of a two feed knitting machine, with some parts removed for the sake of clarity;

Figure 2 is a side elevational view of the mechanism of Figure 1, viewed from the bottom thereof;

Figure 3 is a side elevational view of the mechanism of Figure 1, substantially from the left hand side thereof;

5 Figure 4 is an elevational view, showing details of the novel yarn clamp of the present invention;

Figure 5 is a plan view of a portion of the dial cap, illustrating the novel guide element provided below the yarn handling device;

10 Figure 6 is a sectional view taken on the line 6—6 of Figure 5;

Figure 7 is an elevational view, partly broken away, illustrating the air control means of the present invention;

15 Figure 8 is an elevational view of the air valve operating, latching and tripping mechanism of Figure 7, on enlarged scale;

Figure 9 is a side elevational view, partly diagrammatic, of the shear operating mechanism;

20 Figure 10 is an elevational view of the mechanism of Figure 9, viewed from the left-hand side thereof; and

Figures 11 to 16 are plan views sequentially illustrating the operation of the invention through a yarn change.

25 Referring to the drawings in detail, Figures 1, 2 and 3 illustrate a portion of a conventional multiple feed seamless hosiery machine, such as a 400 needle model AMF Scott & Williams two feed machine. As best shown in

30 Figure 1, the latch ring 20 of the machine encloses two knitting stations, which for convenience may be identified as main knitting station 22 and auxiliary knitting station 24, the auxiliary station trailing the main knitting station by approximately 45° in the direction of cylinder rotation, counterclockwise as viewed in Figure 1. At the main knitting station are provided a plurality of

35 yarn fingers which are individually retractable and function as interchangeable yarn feeds. The yarn fingers are pivotally mounted in the usual manner, and actuated in conventional manner by thrust bars maintained in contact with the main pattern drum of the machine. While six or more yarn fingers are customarily provided, only

40 two are illustrated. As shown in Figures 1 and 3, main knitting station yarn finger 26 is illustrated in active position, feeding yarn 28 to the needles 30, and yarn finger 32 is illustrated in inactive position, the inactive yarn 34 extending therefrom to the dial cap of the machine in usual manner.

45 At the auxiliary knitting station 24 are provided the yarn finger 36 in active position, feeding yarn 38 to the needles 30, and the yarn finger 42 in inactive position, with inactive yarn 44 extending therefrom. As will be

50 understood, other active and inactive yarns may be present, but are unnecessary for an understanding of the present invention. The needles 30 are independently mounted in the rotary cylinder of the machine (not shown), and extending thereabove adjacent the periphery of the dial 55 and the dial cap 46. The usual dial drive pinion 48 is mounted on the upper end of dial drive shaft 50, which serves to effect rotation of the dial and its transfer jacks in synchronism with the cylinder. All of the foregoing elements are conventional.

60 Mounted on the dial cap, at a position near the periphery thereof and trailing the auxiliary knitting station 24 by approximately 90° , is a yarn handling device indicated generally as 60. The yarn handling device is of the type disclosed in my copending application, Serial No.

65 650,212, filed April 2, 1957, and functions in similar manner, although in the present invention the yarn handling device handles yarns from both the main and the auxiliary knitting stations. As disclosed in detail in my copending application referred to, the yarn handling device includes a block or housing 62, the block having a

70 horizontal bore extending therethrough, an air pressure conduit 64 leading thereto, and an exhaust conduit 66

leading therefrom. A small diameter tube 68 branches off from the pressure conduit 64 and terminates in a nozzle 70, directed slightly downwardly against the underlying dial cap and generally in the direction of cylinder rotation. As shown in Figure 1, the nozzle 70 is disposed adjacent the periphery of the dial cap 46, and accordingly near the encircling needles 30 of the machine.

The block 62 houses a piston 72, which extends above the top of the block, below the pivotally mounted clamp arm 74. From the free end of clamp arm 74 extends a downwardly directed extension 76, best shown in Figure 3. A branch passage 78 extends to the under surface 80 of the block 62, the under surface of the block being spaced slightly from the dial cap 46. A guide post 82 extends downwardly from the block to the dial cap, adjacent the opening of branch passage 78. As described in detail in my copending application referred to, pressure air supplied to the yarn handling device through conduit 64 exhausts through conduit 66 and is effective to induce air flow upwardly into branch passage 78, in other words, to create a vacuum in and below branch passage 78. The pressure air is effective also to elevate the piston 72 and to pivot the clamp arm 74 disposed thereabove, whereby the clamp arm extension 76 is elevated at all times when pressure air is supplied to the device. As will be understood, spring or other suitable means are provided to bias the free end of clamp arm 74 and its extension 76 downwardly at all times. Some of the pressure air also passes through tube 68 and its nozzle 70, creating a jet of air at this point.

In accordance with the present invention, a novel yarn clamp 90 is mounted on the dial cap on the leading side of the yarn handling device, immediately adjacent thereto. The inner end of the yarn clamp encloses a headed pin 92 extending from the dial cap, and is movable with respect to said pin, the upward movement thereof being limited, however, by the head 94. Substantially centrally thereof, the yarn clamp encloses a vertical guide pin 96, and a small spring 98 encircles the guide pin 96 between the yarn clamp and the dial cap, as shown in Figure 4. The spring 98 tends to elevate the yarn clamp, to the maximum distance permitted by the head 94 of pin 92, and the overlying adaptor 100 through which the pressure conduit 64 enters the block 62. Outwardly of the guide pin 96 the yarn clamp extends below the bottom of clamp arm extension 76, and therebeyond the leading edge thereof is formed into a forwardly curved portion 104.

A substantially V-shaped yarn guide 110, which may be formed of wire, extends from the base of pin 92, its outer arm 112 rising slightly from the dial cap, along a line slightly leading the auxiliary knitting station 24. A yarn guide post 114 extends upwardly from the dial cap adjacent yarn clamp 90, the guide post being substantially in line with the auxiliary knitting station and the clamp arm 74, as shown. Below the block 62, an elongated guide element 116 extends above the surface of the dial cap. As shown in Figures 5 and 6, element 116 passes directly below the branch passage 78 and is inclined with respect to the normal yarn path. Conveniently, the guide element may be a section of wire, suitably anchored into the dial cap as shown in Figure 6, and resting directly thereon.

Slightly beyond the yarn handling device 60, and substantially opposite the main knitting station 22, is disposed the yarn shear indicated generally as 120. The yarn shear is peripherally mounted, and of the type disclosed in my copending application referred to. In the exemplary embodiment, due to the skirted configuration of the dial structure, the fixed shear blade 122 is disposed substantially in the slot 124, and the movable shear blade 126 operates in conjunction therewith, pivoting at 128. The skirt 130 in the vicinity of the skirt slot 124, is appropriately bevelled, as at 132.

The movable shear blade 126 is engaged by rod 134 to one end of lever 136, which is pivotally mounted near its

center on a stud 138 extending from the block 62. The opposite end of lever 136 is engaged by rod 140 to an operating lever 142, which in turn is pivotally mounted at 144.

The disposition of the yarn handling device 60 and shear 120, as illustrated and described, necessitates relocation of the pin customarily extending downwardly from the overhanging bracket arm of the machine to the dial cap 46, to preclude rotation of the dial cap and the elements mounted thereon. In accordance with the present invention, this pin (not shown) may be relocated on a bracket extending from the overhanging bracket arm, downwardly into the dial cap socket 146, shown in Figure 1.

The air control mechanism of the invention is illustrated in Figures 7 and 8. As there shown, a conventional air valve 150 is mounted on a plate 152 which in turn is supported by a frame mounted bar 154, adjacent the main timing drum 156 of the machine. The air valve 150 is provided with a plunger 158, which is internally biased to outward valve closed position. The valve is substantially T-shaped, and as will be understood a source of air pressure is connected to one side thereof and the pressure conduit 64 extends from the other side thereof to the yarn handling device 60.

A lever arm 160 is pivotally mounted at 162 on the bar 154, one end of the lever arm being maintained in contact with the timing drum 156 by a spring 164 suitably engaged to the other end of the lever arm. The lever arm is in alignment with the head 166 of valve plunger 158, and may be formed into a cam surface 168 adapted to bear against the valve plunger head. Adjacent the lever arm 162, a hand lever 170 is pivotally mounted at 162, the hand lever also being aligned with and engaging the valve plunger head 166, and being formed into an outwardly extending tail 172. A latch bracket 174 is fixed to the side of hand lever 170, and a suitably shaped latch 176 extends laterally therefrom. Spring 178 extends from the latch 176 to the valve mounting structure, whereby the latch and the associated hand lever are maintained in contact with valve plunger head 166, although with insufficient pressure to depress the valve plunger 158 and open the valve.

A latch arm 180 is pivotally mounted at 182 on the valve mounting structure, and extends below the latch 176. The latch arm 180 is formed into a latch engaging shoulder 184 and outwardly thereof into an upwardly offset riding surface 186, and a spring 188 biases the latch arm 180 upwardly at all times to maintain it in contact with the latch 176.

Referring to Figure 7, 190 is a rotary shaft of the machine which rotates at one-fourth the speed of the needle cylinder. The shaft 190 is provided with a boss 192, and a rocker arm 194 is pivotally mounted thereabove at 196. Spring or other suitable means are provided to maintain the associated end of rocker arm 194 in contact with the boss 192. A racking pawl 198 extends from the other end of rocker arm 194 into contact with the graduating cam of the machine, which is not shown but which is in alignment with the timing drum 156. Opposed cams 200 are provided on the periphery of boss 192, adapted to engage and rock arm 194 periodically. The shaft 190, boss 192, rocker arm 194, racking pawl 198, and the cams 200 are standard elements of the model AMF machine with which the instant invention is illustrated. In applying the invention to this machine, the rocker arm 194 may conveniently be extended, as at 202, and a rigid rod 204 provided between the rocker arm extension 202 and side pad 206 mounted on the latch arm 180. In this manner, means are conveniently provided for periodically depressing the latch arm, and it will be evident that equivalent trip means may be provided in association with any other moving part of the machine. The timing drum is provided with cams 208 in alignment with lever arm 160, the cams being adapted

to displace the associated end of the lever arm away from the drum in the usual manner.

To utilize a single shear to cut all yarns of the exemplary two feed machine, it is necessary to provide for normal shear operation in time with movement of the timing drum, and also to provide alternatively for delayed operation of the shear, that is for shear operation while the drum is stationary. In the model AMF machine, makeup is accomplished with a series of intermittent and brief auxiliary drum movements, which are long enough to permit dropping yarns in or taking yarns out at both stations, but not long enough to permit the yarns to reach the position of yarn shear 120. It is accordingly necessary to provide delayed action shearing during the makeup. Alternative means for shear operation are illustrated in Figures 9 and 10.

As shown in Figure 9, the operating lever 142 which is engaged to the movable shear blade 126 through rod 140 is engaged and actuated in normal manner by a thrust rod 210, which is maintained in contact with the timing drum 156 and elevated periodically by drum cams 212. The thrust rod 210 passes through a guiding passage in the guide bar 214, and a spring extending from the guide bar to the thrust rod, urges it downwardly into contact with the timing drum. As will be understood, periodic movement of the timing drum in clockwise direction, as viewed in Figure 9, brings successive cams 212 under the thrust rod 210 and elevates the thrust rod to the top of a cam, the elevated position of the thrust rod being indicated in dotted lines in Figure 9. The upward movement of the thrust rod rocks the operating lever 142 in clockwise direction, moving the rod 140 downwardly and thereby opening the shear. As further movement of the timing drum carries the cam 212 out from under the thrust rod 210, the thrust rod returns to normal position riding the drum, permitting the shear to close. As disclosed in my copending application referred to, the trailing end of the shear operating cam 212 may be stepped or sloped, to permit closing of the shear over a space of time corresponding to the passage of several needles, for a purpose presently evident.

As illustrated in Figure 10, the end of operating lever 142 over the thrust rods may be provided with a transverse pad 216, whereby the operating lever is adapted to be engaged by a thrust rod 218, as well as by the thrust rod 210. In the drawings, the thrust rods 210 and 218 are relatively widely spaced for the purpose of clarity of illustration, but it will be understood that in practice the thrust rods may be closely adjacent, and in place of the pad 216, two adjoining operating levers may be tied together to function as one, under the impetus of either associated thrust rod.

The thrust rod 218 is utilized to effect shear closing after short auxiliary drum movements have terminated, as during makeup. As shown in Figure 10, the guide bar 214, behind thrust rod 218, is cut away or slotted at 220, to permit rearward movement of the thrust bar, and an additional spring 222 extends from thrust rod 218 forwardly to the guide bar 214, to urge thrust rod 218 forwardly and maintain it when permitted in normal position. A collar 224 is provided on the rotary shaft 190 in alignment with the thrust rod 218, the collar having opposed convex cams 226 thereon, and a cam 228 is provided on the forward edge of thrust rod 218 in the vicinity of collar 224. The cams 226 and 228 are of such size and disposition that when the thrust rod 218 is in normal position, directly behind the solid line position of thrust rod 210 illustrated in Figure 9, the collar 224 and its cams 226 rotate without striking the thrust rod cam 228. Shear operating cams 230 are provided on the timing drum in alignment with the thrust rod 218, and it will be understood that a brief movement of the timing drum is adequate to elevate the thrust rod 218 onto a cam 230 and into shear opening position. The timing drum movement may then termi-

nate in such relationship. Elevation of the thrust rod 218, however, displaces its cam 228 into the path of the cams 226, so that a brief interval after elevation of the thrust rod and termination of the timing drum movement, one or the other of cams 226 will strike the thrust rod cam 228, and displace the thrust rod 218 rearwardly, to the dotted line position 218' shown in Figure 9. This rearward movement of the thrust rod 218 is permitted by slot 220 and resisted by spring 222, which is effective on subsequent movement of the timing drum to restore the thrust rod to normal position. As will be understood, rearward displacement of the thrust rod 218 is effective to drop its bottom end off the cam 230 therebelow, whereby the thrust rod drops into contact with the drum (although at position rearward of normal) and permits the shear to close. In this manner, a brief interval of time between termination of the timing drum movement and shear closing is provided.

Function and operation of the invention will now be described in detail, in connection with an ordinary yarn change during two feed knitting. Normal operation of the machine is illustrated in Figure 1, wherein the yarn fingers 26 and 36 are active, feeding yarns 28 and 38 directly to the needles at their respective knitting stations. From the retracted finger 32 at main knitting station 22, the inactive yarn 34 extends under yarn guide 110, around yarn guide post 114, under yarn clamp 90, alongside guide post 82 and upwardly into branch passage 78 of the yarn handling device. From retracted yarn finger 42 at the auxiliary knitting station 24, inactive yarn 44 extends under yarn clamp 90, alongside guide post 82, and upwardly into the branch passage 78. As will be understood, the ends of inactive yarns 34 and 44 and all other inactive yarns extend through the yarn handling device block 62 and into the exhaust conduit 66.

During normal operation of the device as described, the lever arm 160 of the air control mechanism is riding a cam 208 of the timing drum 156, and latch 176 associated with the hand lever 170 is riding the surface 186 of the latch arm 180. The plunger 158 of valve 150 is extended, whereby the valve is closed and air is cut off from the yarn handling device 60. It will be understood that periodic depression of rod 204 by the movement of rocker arm 194 (Figure 7) merely depresses the latch arm 180, the latch arm being returned to the position illustrated in Figure 8 after each depression by its spring 188. The yarn shear 120 during normal operation is closed, both thrust rods 210 and 218 riding the surface of drum 156, the end of operating lever 142 engaged to the shear being in elevated position.

When the machine comes to a yarn change, initially the yarn finger 32 is dropped to active position at the main knitting station 22, whereby the formerly inactive yarn 34 is taken by the needles, the first needle to knit this yarn being indicated in Figure 11 as 30'. Substantially simultaneously, the drum movement effecting the yarn change carries the engaged cam 208 out from under the lever arm 160 of the air control mechanism, permitting spring 164 to force the opposite end of the lever arm 160 against the timing drum 156. This movement of the lever arm 160 causes its cam surface 168 to depress the head 166 of the valve plunger 158, opening valve 150, whereupon pressure air flows through conduit 64 to yarn handling device. As described in my copending application referred to, access of pressure air to the yarn handling device 60 induces suction and air flow upwardly into the branch passage 78, and a high velocity air flow outwardly through exhaust conduit 66. The resultant suction and air flow engages the ends of the inactive yarns, particularly yarns 34 and 44, and tensions these yarns, assuring positive yarn laps. Simultaneously, the pressure air elevates piston 72 and the associated clamp arm 74, whereby the clamp arm

extension 76 rises from the clamp 90, releasing the yarns extending therebelow. The small spring 98 below the yarn clamp 90, it will be understood, cooperates to elevate the yarn clamp a short distance from the dial cap surface. The access of pressure air to the yarn handling device also causes a jet of air to issue from nozzle 70 of the tube 68, this air flow having no function at this stage of the operation.

When valve 150 is opened by the lever arm 160, the hand lever 170 follows the valve plunger head 166, by action of spring 178, displacing the associated latch 176 to the right as viewed in Figure 8, beyond the shoulder 184 of latch arm 180. When this occurs, spring 188 elevates the latch arm 180 to latching position, retaining the hand lever 170 in valve opening position. Periodic depression of rod 204 will lower the latch arm 180 out of engagement with latch 176, but so long as the valve 150 is maintained open by lever arm 160, the hand lever 170 will remain in place against the valve plunger head 166, in inward position, and will be re-engaged by the shoulder 184 of the latch arm 180 upon its return to elevated position.

Simultaneously, or briefly thereafter, a drum cam 212 passes under and elevates the thrust rod 210 (Figure 9), rocking the operating lever 142 to open yarn shear 120. As seen in Figures 1, 2 and 3, downward movement of the associated end of operating lever 142 depresses rod 150 to rotate lever 136, and the other end of lever 136 acts through rod 134 to elevate the movable shear blade 126 about its pivot 128. The shear remains open throughout the remainder of the yarn change, closing as one of the final movements thereof.

Momentarily after the yarn 34 is dropped into the needles at the main knitting station 22, the previously active yarn 28 is withdrawn therefrom, by retraction of its yarn finger 26. Desirably, the previously active yarn is withdrawn 10 or 15 needles after the hitherto inactive yarn is inserted, providing a yarn lap of about one-half inch. Some adjustment of the yarn finger operating cams of the machine may be required to achieve short yarn laps of this order, the machine normally providing longer yarn laps in order to avoid misses. In operation of the present invention, no yarn laps are missed, even though the laps are less than one-half inch. Figure 12 illustrates the relationship of the elements immediately after yarn 28 has been withdrawn from knitting by retraction of finger 26. It will be noted that the newly inserted yarn 34 has been carried a short distance around the needle circle by needle 30', and the yarn end has been partially withdrawn from under the yarn guide 110. The resultant slack in the end of yarn 34 is taken up by the yarn handling device 60, which takes up the yarn end as permitted.

When needle 30', the first needle to take the yarn 34 newly inserted at the main knitting station, reaches the auxiliary knitting station 24, the inactive yarn 44 is dropped into the knitting by its yarn finger 42, the machine being adjusted to drop this yarn in, at or close to the needle 30'. Figure 13 illustrates the relationship of the yarns and yarn fingers immediately after yarn finger 42 has been dropped to active position, and the yarn 44 inserted into the needles for knitting. As shown, the yarn 44 has been dropped into the knitting two needles behind needle 30'. It will be noted that at this point the end of yarn 34 has been carried by needle 30' completely out from under yarn guide 110, and through this movement the yarn end is tensioned and slack therein taken up by yarn handling device, as previously described. It will be further noted that the trailing end of the yarn 28 newly withdrawn at the main knitting station, extending from the needles to the now retracted yarn finger 26, is in position to be guided below the yarn guide 110.

Shortly after the yarn 44 is dropped into the knitting at the auxiliary station, the yarn 38 is withdrawn from

the knitting by retraction of its yarn finger 36. As in the case of the main knitting station, the machine is adjusted preferably so that the yarn 38 is withdrawn from the knitting approximately 10 to 15 needles after insertion of the yarn 44. As illustrated in Figure 14, the yarn 38 has been withdrawn from the knitting two needles behind the last needle to knit the yarn 28, previously withdrawn at the main knitting station. At the stage of Figure 14, the yarn ends 34 and 44 have been carried by the first needles to knit these yarns beyond the auxiliary knitting station, the yarn handling device maintaining tension and taking up the slack therein. The yarn 28 withdrawn at the main knitting station has by this time passed under the outer arm 112 of the yarn guide 110.

Figure 15 illustrates the relationship of the yarns when the needle 30' has reached a position substantially opposite the yarn handling device 60. At this time, the yarn 28 withdrawn from the knitting at the main knitting station is engaged in the V of yarn guide 110, wrapped slightly around the guide post 114, and has passed under the outer end of the yarn clamp 90. The yarn 38 withdrawn from the knitting at the auxiliary knitting station 24 has passed under the outer end of yarn clamp 90. The curved outer portion 104 of the yarn clamp insures that the yarns drawn therepast by the needles go under the yarn clamp. The ends extending from the newly inserted yarns 34 and 44 are disposed substantially radially of the branch passage 78 of the yarn handling device, and all slack in the free yarn ends has been taken up in the branch passage 78 and the exhaust conduit 66, whereby effective tension is maintained on these yarns. It will be noted that the yarn guide 110 and guide post 114 tend to separate yarns extending from retracted yarn fingers of the main knitting station from yarns extending from retracted yarn fingers of the auxiliary knitting station. In actual operation, inactive yarns from the respective knitting stations are thereby maintained in separated bundles, passing under the yarn clamp 90 side by side.

Figure 16 illustrates the relationship of the yarns and other elements when the needle 30' has reached a position close to the pivotal axis of the yarn shear 120. In moving from the position of Figure 15 to the position of the position of Figure 16, the yarn ends 34 and 44 are withdrawn from the branch passage 78, against the tensioning resistance of air movement. The yarn 28 newly withdrawn at the main knitting station extends under arm 110, around guide post 114, under yarn clamp 90, alongside the guide post 82 below the block 62, and then below the branch passage 78 to the last needle to take this yarn. The yarn 38 newly withdrawn at the auxiliary knitting station extends under the yarn clamp 90, alongside the guide post 82, and below branch passage 78 to the last needle to take this yarn. As described in my copending application previously referred to, the suction effect below branch passage 78 of the yarn handling device is effective to engage and lift the yarns 28 and 38 extending thereunder, to tension these yarns. This function is enhanced by the guide element 116 disposed below branch passage 78, which serves to raise these yarns slightly from the surface of the dial cap. It has been found that the newly withdrawn yarns, due to the influence of lubricant or other factor, may tend to adhere to the surface of the dial cap and resist the tensioning effect of the air flow below the branch passage. The novel guide element 116 prevents this, separating these yarns from the dial cap as they are drawn under the yarn tensioning device to insure that the yarns are suitably engaged and tensioned.

The air blast issuing from nozzle 70 is effective at this time to belly out the yarns where they extend inwardly from the needles. This air blast sweeps across the peripheral portion of the dial cap in the vicinity of the shear, in the direction of needle rotation, engaging the

yarns sufficiently to insure that they extend substantially radially inwardly from the needles. The blast effect of the nozzle is balanced by the restraining suction effect of the yarn handling mechanism on the yarns, with the net result that the yarns assume the relative positions illustrated in Figure 16. It will be understood that if the yarns extended in straight lines from the engaged needles to the branch passage 78, they would be disposed across the shear blades at acute angles. Under these circumstances, even though the shear is disposed closely adjacent the needle circle, on severing the yarns the cut ends extending from the fabric would be considerably greater in length than the radial distance from the shear to the needles, due to the inclination of the yarns. The effect of the air blast on the yarns, then, is to position them for shearing in such manner that the cut ends remaining on the fabric are of absolute minimum length.

Shear operation is timed to take place at about the time when the yarns are in the position of Figure 16. Desirably, closing of the shear is initiated slightly before the needle 30' reaches the position of Figure 16. At this point, the cam 212 passes out from under the thrust rod 210 (Figure 9) permitting the operating lever 142 to rotate counterclockwise as viewed, and to close the shear. Since the last needle to take the auxiliary knitting station yarn 38 may trail the needle 30' by an inch or more, the difficulty of cutting all four yarns with a single shear stroke will be apparent. The size of the shear blades have, of course, a practical limit, and the yarn 38 may not be positioned for shearing when the yarn 34 reaches the last possible position for shearing. For this reason, it is desirable to close the shear gradually over a discrete time interval. This may be conveniently accomplished by suitably sloping the trailing end of the shear operating cam 212, or providing a stepped configuration therein. This results in relatively gradual closing of the shear, whereby the movable shear blade 126 pivots to closed position over an appreciable period of time corresponding to the passage of several needles. Shear closing may in this manner be timed to initiate shearing immediately prior to the point illustrated in Figure 16, and to complete the shear stroke a few needles after the momentary position illustrated in Figure 16, thereby insuring that all four yarns are sheared in a single stroke, leaving cut ends on the fabric of less than one-half inch in length.

After shearing, the severed ends from yarns 34 and 44 are picked up through branch passage 78 and exhausted through exhaust conduit 66 of the yarn handling device, to a screen receptacle or the like. The cut ends of the newly withdrawn yarns 28 and 38, extending from the now retracted yarn fingers 26 and 36, are engaged in the branch passage 78 and sucked up therethrough into the yarn handling device and its exhaust conduit 66, to the former position of yarns 34 and 44.

Finally, at the end of the drum movement effecting the yarn change, a cam 208 passes under the lever arm 160 of the air control mechanism (Figures 7 and 8) and displaces the lever arm to the position shown in Figure 8. The valve 150 is prevented from closing immediately, its plunger 158 being held in by the hand lever 170, the associated latch 176 being engaged against the shoulder 184 of latch arm 180. That is, upon retraction of the lever arm 160 therefrom, the valve is momentarily latched in open position by hand lever 170 and latch arm 180.

Briefly thereafter, the rocker arm 194 is displaced by one or the other of cams 200, displacing the rod 204 and the engaged latch arm 180 downwardly. The latch 176 is in this manner tripped, and the valve 150 is permitted to close, its plunger 158 and its head 166 moving outwardly and returning the hand lever 170 to the position illustrated in Figure 8. In this manner, air flow to the yarn handling device may be maintained slightly beyond the duration of the drum movement, insuring that the

shearing operation is completed and that all yarns are engaged, cleared, and tensioned before the air flow is cut off.

The closing of valve 150, of course, terminates the flow of air through nozzle 70, and permits the piston 72 to retract, whereby the clamp arm 74 may be rotated by its spring to bring its extension 76 into firm contact with yarn clamp 90, whereby all yarns extending thereunder are mechanically and positively clamped. The clamp pressure persists until the next yarn change, when pressure air is again admitted to the yarn handling device.

The hand lever 170 is useful for manual opening of the valve 150, to permit air flow. An attendant may at any time, in threading or adjusting the machine or the like, lift the hand lever tail 172 to open the valve.

The foregoing completes the description of an ordinary yarn change during two feed knitting. As previously indicated, makeup on the illustrative machine is effected by drum movements of very short duration. In starting a stocking, for example, yarns may be dropped in at both knitting stations, but the drum movement terminates before these yarns reach the position of shear 120. For this and similar operations in makeup or otherwise, the shear may be actuated by the thrust rod 218. As previously described, a brief movement of the timing drum suffices to move a cam 230 under and to elevate the thrust rod 218 and open the shear. Shortly thereafter, the thrust rod is rearwardly displaced and knocked off the cam by the action of shaft 190, permitting the shear to close. The time interval thus provided is sufficient to permit the yarns to reach the position of the shear, although the timing drum movement has terminated previously. Either alternative method of operating the yarn shear may be employed at any stage in the knitting cycle, as they operate independently of each other.

It will be thus seen that there has been provided by this invention apparatus and methods in which the various objects hereinbefore set forth, together with many practical advantages, are successfully achieved. As various possible embodiments may be made of the several features of the above invention, all without departing from the scope thereof, it is to be understood that all matter hereinbefore set forth or shown in the accompanying drawings is to be interpreted as illustrative, and not in a limiting sense.

What is claimed is:

1. In a circular knitting machine, a rotary cylinder with independent needles, a dial cap mounted adjacent the top of said cylinder, a first group of individually retractable yarn feeds, a second group of individually retractable yarn feeds angularly spaced from said first yarn feed group in the direction of cylinder rotation, a timing drum controlling the movement of said yarn feeds, a shear disposed peripherally of said dial cap at a point angularly spaced from said second yarn feed group in the direction of cylinder rotation, means actuated by said drum for opening said shear, means for closing said shear when said drum is stationary, a yarn handling device mounted above said dial cap between said second yarn feed group and said shear, an air line leading to said yarn handling device, a valve in said air line, means actuated by said drum for opening said valve, and means for closing said valve when said drum is stationary.

2. A circular knitting machine as defined in claim 1, wherein said yarn handling device includes a housing, a horizontal bore extending through said housing, said air line communicating with one end of said bore, an exhaust conduit communicating with the other end of said bore, and a branch passage extending downwardly from an intermediate section of said bore and opening above said dial cap.

3. In a circular knitting machine, a dial cap and a yarn handling device mounted above said dial cap, said yarn handling device including a housing, a horizontal

bore extending through said housing, a pressure conduit communicating with one end of said bore, an exhaust conduit communicating with the other end of said bore, a branch passage extending downwardly from an intermediate section of said bore and opening above said dial cap, a yarn clamp mounted on said dial cap adjacent said housing, a clamp arm pivotally mounted on said housing for vertical movement, resilient means urging said clamp arm downwardly into contact with said yarn clamp, resilient means between said yarn clamp and said dial cap adapted to elevate said yarn clamp a limited distance when said clamp arm is elevated, a vertical bore in said housing, a piston in said vertical bore, said piston engaging said clamp arm whereby upward movement of said piston will elevate said clamp arm, and a passage in said housing providing communication between said pressure conduit and the bottom of said vertical bore.

4. In the operation of a circular knitting machine having a rotary cylinder with independent needles, a dial cap mounted adjacent the top of said cylinder, a first group of individually retractable yarn feeds, and a second group of individually retractable yarn feeds angularly spaced from said first group in the direction of cylinder rotation, the method comprising the steps of applying tension to yarns extending from both yarn feed groups over said dial cap by suction applied at a common point, and inserting said yarns into the needles for knitting while so tensioned.

5. In the operation of a circular knitting machine having a rotary cylinder with independent needles, a dial cap mounted adjacent the top of said cylinder, a first group of individually retractable yarn feeds, and a second group of individually retractable yarn feeds angularly spaced from said first group in the direction of cylinder rotation, the method comprising the steps of removing yarns from active knitting by retraction of a yarn feed of each of said yarn feed groups, whereby said withdrawn yarns are carried by the last needle to knit each yarn around said cylinder and over said dial cap, applying tension to said withdrawn yarns by suction applied at a common point trailing said second yarn feed group, severing said withdrawn yarns close to the fabric while so tensioned, and engaging the severed yarn ends by means of said suction.

6. In the operation of a circular knitting machine having a rotary cylinder with independent needles, a dial cap mounted adjacent the top of said cylinder, a first group of individually retractable yarn feeds, a second group of individually retractable yarn feeds angularly spaced from said first group in the direction of cylinder rotation, and yarn severing means disposed peripherally of said dial cap at a point angularly spaced from said

5 second yarn feed group in the direction of cylinder rotation, the method comprising the steps of applying tension to inactive yarn ends extending from both yarn feed groups over said dial cap by suction applied to a common point trailing said second yarn feed group and leading said yarn severing means in the direction of cylinder rotation, inserting inactive yarns from each of said yarn feed groups while so tensioned into the needles for knitting, withdrawing yarns from active knitting by retraction of a yarn feed of each of said yarn feed groups, whereby said withdrawn yarns are carried by the last needle to knit each yarn around said cylinder and over said dial cap, applying tension to said withdrawn yarns by suction applied at said common point, severing all of said yarns close to the fabric while so tensioned, removing the severed newly inserted yarn ends by means of said suction, and engaging the severed withdrawn ends by means of said suction.

7. In the operation of a circular knitting machine having a rotary cylinder with independent needles, a dial cap mounted adjacent the top of said cylinder, a first group of individually retractable yarn feeds, a second group of individually retractable yarn feeds spaced from said first group in the direction of cylinder rotation, and a shear disposed peripherally of said dial cap at a point angularly spaced from said second yarn feed group in the direction of cylinder rotation, the method comprising the steps of applying tension to inactive yarn ends extending from both yarn feed groups over said dial cap at a point trailing said second yarn feed group and leading said shear in the direction of cylinder rotation, inserting inactive yarns from each of said yarn feed groups while so tensioned into the needles for knitting, withdrawing yarns from active knitting by retraction of a yarn feed of each of said yarn feed groups, whereby said withdrawn yarns are carried by the last needle to knit each yarn around said cylinder and over said dial cap, applying tension to said withdrawn yarns, and shearing all of said yarn ends sequentially by a single stroke of said shear.
